[57] CLAIM

The ornamental design for a digital disk player, as shown and described.

DESCRIPTION

FIG. 1 is a top, front and right side perspective view of a digital disk player according to our design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a bottom plan view thereof; and,

FIG. 8 is a view similar to FIG. 1 illustrating the digital disk player hereof with the cover in an open position.

*FIG. 2**FIG. 3**FIG. 4**FIG. 5**FIG. 6**FIG. 7**FIG. 8*
